UNITED STATES PATENT OFFICE.

MERLE MELVIN NEWTON, OF COLORADO SPRINGS, COLORADO, ASSIGNOR TO ALFRED OSTENDORF AND LAWRENCE L. CRAGIN, BOTH OF COLORADO SPRINGS, COLORADO.

GAME APPARATUS.

Application filed March 11, 1925. Serial No. 14,795.

To all whom it may concern:

Be it known that I, MERLE M. NEWTON, a citizen of the United States, and a resident of Colorado Springs, in the county of El Paso and State of Colorado, have made certain new and useful Improvements in Game Apparatus, of which the following is a specification.

My present invention relates generally to game apparatus, and more particularly to a simple, inexpensive and amusing apparatus which requires skill, steady nerves and patience, and is calculated to stimulate all three, and a further object is the provision of a game apparatus of the above type which may be made strong and of a durable nature.

In the accompanying drawing which illustrates my present invention and forms part of this specification:—

Figure 1 is a top plan view showing the game board as proposed by my invention;

Figure 2 is a longitudinal section taken centrally therethrough, substantially on line 2—2 of Figure 1;

Figure 3 is a vertical transverse section taken therethrough substantially on line 3—3 of Fig. 1; and,

Figure 4 is a detailed view of one of the rolling pieces.

Referring now to these figures, and particularly to Figs. 1, 2 and 3, my invention proposes a game apparatus including a game board generally indicated at 10, and preferably of the generally rectangular form shown, which board may be made solid and substantial and is supported at its opposite ends upon transversely disposed rockers 11 and 12. The rocker 12 is of somewhat greater height than the rocker 11, and the game board is thus supported for laterally swinging or tilting movements, and inclined from one end to the other, the lower end being the starting end and the higher end being the finishing end.

Upon the surface of the game board 10 between the raised end ledges 13 and 14, are arranged longitudinal rows of slightly angular and generally transverse upstanding ribs 15, the ribs of the several rows overlapping one another and forming between them approximately diamond-shaped receiving spaces 16. The ends of the several ribs are spaced from the adjacent ribs to form channels 17, communicating between the re-

ceiving spaces 16, although it will be noted that in certain instances, as indicated at 18, the angular ribs of adjacent rows are connected to one another transversely of the game board, the connecting channels 17 being omitted at these points.

As indicated in Fig. 2, the receiving spaces 16 have their bases inclined in inverse relation to the inclination of the game board 10 and as seen particularly in Figures 1 and 3, the ribbed area of the game board, or more particularly the playing surface of the game board has along its opposite sides lengthwise gutters 19, which are sufficiently deep and sufficiently well defined to prevent a playing piece from ejection from either of the gutters after it has once fallen into the same in the ordinary playing of the game.

With the game board as thus described, playing pieces are utilized, each of the spherical form indicated at 20 in Figure 4, so as to adapt the same to roll freely on the surface of the game board along the ribs 15 within the receiving spaces 16, and through the connecting channels 17.

In playing the game, the game board is placed upon a level surface and thereafter during play its manipulation is limited to transverse rocking or tilting movements on the rockers 11 and 12.

A piece 20 is placed at the lower portion of the game board against the lower ledge 13 and it is the object to make this piece climb the surface of the game board toward the receiving end, or in other words against the upstanding ledge 14 into one of the receiving spaces immediately adjacent to this latter ledge. In such play, if properly and skillfully accomplished, the piece 20 is caused to roll along angular lines first in one direction and then in the other, climbing the surfaces of the ribs 15 in its tortuous upward path to the upper end of the board. In the course of this movement, hazards are interposed by virtue of the connected ribs 18, forcing the player to shift the playing piece near to the side edges of the playing surface with the ever present danger of the rolling piece finding its way into one of the side gutters 19. Should one of the pieces fall into the gutter it immediately rolls back to the lower starting end of the board, but if by skillful, properly coordinated movements of the game board, the player avoids such a consequence, and continues

upward movement of the playing piece, the upper receiving end of the board will finally be reached, and the desired end thus achieved.

5 The upper and lower upstanding ledges 13 and 14 may if desired be provided with small counters as indicated at 21, and other means may be employed to further the convenience of those engaged in play.

10 It is obvious that the game board as described may be made strong and of a lasting or durable nature, and it is possible for this purpose to construct the same from a single piece of material with its surface

15 suitably grooved, recessed or indented to form the ribs 15 receiving spaces 16 and connecting channels 17. It is also obvious

20 that the rockers 11 and 12 not only act to support the game board in lateral swingable or tilttable relation and longitudinally in- 25

20 the game board, across the lower portion of the ends of which they are connected.

25 I claim:—

1. A game including a game board and through said channels, said ribs being dis- 30

rolling pieces, the board having rockers and being swingable on said rockers in a trans- 35

30 movement of pieces on the board, said board being higher at one end than at the other, 35

35 and said board also having lengthwise gut- 40

40ters at the opposite sides of its ribbed area, 45

45

45

being higher at one end than at the other and having its surface provided with longitudinal rows of angular ribs upstanding therefrom and disposed in generally trans-

50 verse overlapping relation, said ribs forming between them receiving spaces for the rolling pieces and having the ends thereof spaced from adjacent ribs to form connecting channels between said receiving spaces,

55 and said board also having lengthwise gutters at the opposite sides of its ribbed area and having certain of the ribs of adjacent rows connected to one another across the spaces between the rows whereby to elimi-

60 nate the connecting channels at such points and form additional hazards in the move- 65

ment of the rolling pieces.

3. A game including a laterally tilttable board inclined endwise and having upon its surface lengthwise rows of generally trans- 70

70 verse upstanding ribs of angular form, said ribs forming between them receiving spaces and channels connecting said spaces, and spherical playing pieces for rolling move-
